UNITED STATES PATENT OFFICE

AUGUST BAUER, OF NEW YORK, N. Y., ASSIGNOR OF ONE-HALF TO EDWARD J. SCHMITT, OF NEW YORK, N. Y.

AEROPLANE

Application filed June 5, 1929. Serial No. 368,486.

This invention relates to new and useful improvements in flying machines.

The invention has for an object the provision of a device of the class mentioned, which is of simple durable construction, desirable in use and efficient in action and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:—

Fig. 1 is a front elevational view of a device constructed according to this invention.

20 Fig. 2 is a vertical sectional view taken on the line 2—2 of Fig. 1.

Fig. 3 is a fragmentary side elevational view of Fig. 2.

Fig. 4 is a fragmentary detail plan view 25 of a portion of one of the wings of the device.

Fig. 5 is a fragmentary vertical sectional view taken on the line 5—5 of Fig. 1.

Fig. 6 is a fragmentary horizontal sectional view taken on the line 6—6 of Fig. 3.

30 Fig. 7 is a plan view of the device.

The reference numeral 10 indicates generally a tunnel member having a rear opening and a much larger front opening. A pilot's chamber 11 is attached upon the tunnel member and extends to the front thereof. This pilot's chamber is of smaller width than the tunnel member so as to provide air passages at the sides shown in Fig. 1. A seat 12 is arranged within the pilot's chamber and a 40 pilot 13 is shown occupying the seat.

Main wings 14 are attached upon the sides of the tunnel member. Parallel spaced vertical walls 15 connect with the rear portion of a tunnel member and extend materially to the rear. These walls are reinforced by horizontal ribs 16. A horizontal tail wing 17 connects with the rear portion of the walls 15. The outer tips 18 of the main wings are separate from the other portions and are 45 hingedly connected as at 19.

One of the hinged sections 18 connects with an upper wire 20 and with a lower wire 21, both wires leading to the pilot's chamber and one of these wires being wound in one direction upon a drum 22 on a steering rod 23 operable by the pilot, the other of the wires being wound upon the drum in the opposite direction to the first wire so that when the pilot turns the steering rod 23 in one direction the wing section 18 will be moved upwards and when the steering rod is turned in the opposite direction the section will be moved downwards.

The other hinged section 18 is similarly connected with wires 20' and 21' engaged upon a drum 22' mounted upon a steering rod 23' also operable by the pilot. This arrangement permits individual control of the sections 18 on the ends of the main wing. In plan view as seen in Fig. 7 the inner ends of the sections 18 are adjacent the outer ends of the main wing and the lines of contact are inclined from the front of the machine diverging towards the rear.

A curved passage 24 passes thru the tunnel member 10 and an adjustable top vane 25 with air channels 26 engages in the top of the curved passage. Within the passage, central and bottom vanes 27 and 28, respectively are stationarily mounted. These vanes are provided with air channels 26. The top vane 25 is fixed upon a shaft 29 provided with a worm wheel 30 meshing with a worm pinion 31 upon a shaft 32. The shaft 32 is rotatively mounted and extends within reach of the pilot. A hand wheel 33 is provided on the end of this shaft. The air channels 26 provide large surfaces for passing currents of air to engage against and stabilize the machine.

A horizontal bottom propeller 34 is disposed within the bottom of the passage 24 and is mounted upon a shaft provided with a pulley 35. This pulley connects with a belt 36 connected with another pulley upon the shaft of a motor 37. A vertical propeller 38 is mounted upon the shaft of the said motor. The motor is disposed within the tunnel 10 and the vertical propeller 38 rotatively engages in the rear end of the tunnel.

A landing gear wing 39 is pivotally mounted intermediate of its ends as at 40 upon a pair of brackets 41 depending from the tunnel member 10. These brackets are provided with arcuate slots 42 engaged by pins 43 projecting from the wing 39. Front wheels 44 engage upon the front of the wing 39 and rear springs 45 upon the rear of the wing. These springs are firmly connected with vertical pegs 46. These pegs have slots 47 engaged by transverse shafts 48 supporting rear wheels 49. The wing 39 has an opening 50 permitting the peg 46 to move upwards if the springs 45 flex during landing.

A rack 51 is slidably mounted in the pilot's chamber and connects with a spring 52 connected with the wing 39. The rack 51 meshes with a gear 53 on a shaft provided with a worm wheel 54. The worm wheel meshes with a worm pinion 55 upon a shaft 56 rotatively mounted and provided with a collar 57 having a plurality of peripheral apertures. The shaft 56 is connected by bevel gears 58 to a steering rod 59 arranged in the vicinity 25 of the pilot and provided with a steering wheel 60. A latch 61 is arranged to engage in the apertures of the collar 57 for latching the shaft 56 against rotation. The latch 61 is connected by a link 62 with a lever latch 30 63.

The tunnel member 10 is provided with side wings 64 fixed upon arbors 65 arranged for rotation. Sprocket wheels 66 are attached upon the arbors 65 and connect with sprocket chains 67 engaging upon sprocket wheels 68. The sprocket wheels 68 are fixed upon shafts rotatively mounted and provided with gears 69. These gears mesh with smaller gears 70 connected with a handle 71 for manual rotation. A spring pawl 72 is arranged for latching the gear 70 against rotation. A top fin is provided upon the main wings 14 and consists of a rear section 73 and a front section 74. Dot and dash lines 75 in Fig. 1 represent elevated positions of the end sections 18 of the wings.

In operation of the device, engine 37 drives propeller 38 for urging the machine forwards. The engine also drives propeller 34 and air currents set up by this propeller act against the top of the landing gear wing 39. This wing may be angularly positioned as indicated by the dot and dash lines in Fig. 2 for directing the air current set up by the propeller towards the front or towards the rear. It is pointed out that component forces are produced by these air currents so as to tend to move the machine.

The pilot may move the lever catch 63 for disengaging the latch 61 and then manually turn hand wheels 60 for adjusting the inclination of the landing gear wing 39 to desirable inclinations. He may also operate the steering rods 23 and 23' for operating the main wing end sections 18.

The amount of air current set up by the propeller 34 may be controlled by manipulation of the hand wheel 33. This changes the inclination of the adjustable vane 25. A change in inclination of the vane causes different amount of air to pass thru the air channels of this vane and the stationary vanes. Handle 71 may be used for adjusting the position of the side wings 64. Adjusting of these wings changes the amount of air entering the tunnel member 10. A change in the supply of this air changes the working effect of the propeller 38.

When I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A flying machine, comprising a body with a passage extending from the top to the bottom, an adjustable vane with air channels mounted in the top of the passage, stationary vanes with air channels mounted within the passage, a motor driven horizontal propeller disposed at the bottom of the passage and an adjustable wing positioned beneath the propeller.

2. A flying machine, comprising a body with a passage extending from the top to the bottom, an adjustable vane with air channels mounted in the top of the passage, said vane being mounted upon a shaft provided with a worm wheel meshing with a worm gear on a shaft having a hand wheel, stationary vanes with air channels mounted within the passage, a motor driven horizontal propeller disposed at the bottom of the passage and an adjustable wing positioned beneath the propeller.

3. A flying machine, comprising a body with a passage extending from the top to the bottom, an adjustable vane with air channels mounted in the top of the passage, stationary vanes with air channels mounted within the passage, a motor driven horizontal propeller disposed at the bottom of the passage, the motor for driving the propeller being positioned outside of the passage, and an adjustable wing positioned beneath the propeller.

4. A flying machine, comprising a body with a passage extending from the top to the bottom, an adjustable vane with air channels mounted in the top of the passage, stationary vanes with air channels mounted within the passage, a motor driven horizontal propeller disposed at the bottom of the passage and an adjustable wing positioned beneath the propeller, and mounted upon brackets and

attached to a rack connected with a system for movement.

5. A flying machine, comprising a body with a passage extending from the top to the bottom, an adjustable vane with air channels mounted in the top of the passage, stationary vanes with air channels mounted within the passage, a motor driven horizontal propeller disposed at the bottom of the passage and an 10 adjustable wing positioned beneath the propeller, and mounted upon brackets and attached to a rack connected with a system for movement, a spring being interposed between the rack and the wing.

15. 6. A flying machine, comprising a body with a passage extending from the top to the bottom, an adjustable vane with air channels mounted in the top of the passage, stationary vanes with air channels mounted within the 20 passage, a motor driven horizontal propeller disposed at the bottom of the passage, and an adjustable wing positioned beneath the propeller, and mounted upon brackets and attached to a rack connected with a system 25 for movement, landing gear wheels being attached on the said wing.

7. A flying machine, comprising a body with a passage extending from the top to the bottom, an adjustable vane with air channels 30 mounted in the top of the passage, stationary vanes with air channels mounted within the passage, a motor driven horizontal propeller disposed at the bottom of the passage and an adjustable wing positioned beneath the propeller, and mounted upon brackets and attached to a rack connected with a system for 35 movement, landing gear wheels being attached on the said wing, certain of the landing gear wheels being resiliently mounted 40 and provided with ground pegs.

8. A flying machine, comprising a body with a passage extending from the top to the bottom, an adjustable vane with air channels mounted in the top of the passage, stationary 45 vanes with air channels mounted within the passage, a motor driven horizontal propeller disposed at the bottom of the passage and an adjustable wing positioned beneath the propeller, and mounted upon brackets and attached to a rack connected with a system for 50 movement, the brackets being formed with arcuate slots engaged by pins projecting from the said wing.

In testimony whereof I have affixed my
55 signature.

AUGUST BAUER.
